UNITED STATES PATENT OFFICE.

WILLIAM E. STEVENS, OF NEW HAVEN, CONNECTICUT, ASSIGNOR TO SARGENT & COMPANY, OF SAME PLACE.

DESIGN FOR COFFIN-TRIMMINGS.

SPECIFICATION forming part of Design No. 21,359, dated February 23, 1892.

Application filed January 27, 1892. Serial No. 419,473. Term of patent 14 years.

To all whom it may concern:

Be it known that I, WILLIAM E. STEVENS, of New Haven, in the county of New Haven and State of Connecticut, have invented a new 5 Design for Coffin-Trimmings, (Case A;) and I do hereby declare the following, when taken in connection with accompanying drawing, to be a full, clear, and exact description of the same, and which said drawing constitutes 10 part of this specification, and represents a face view.

This invention relates to a design for coffin-trimmings, with special reference to the name-plate or to the handle-plate; and the design 15 consists in the configuration and ornamentation, as shown in the accompanying illustration.

At the top and bottom center is the representation of flowers and leaves inclosed within 20 branches of scroll-work. From these center ornamentations branches of scroll-work are represented as running to the right and left around the ends of the plate, those from the lower edge meeting those from the upper edge,

the configuration and ornamentation being 25 alike at both ends. The outline of the plate corresponds to the line of the scroll-work, which forms a border around the plate, all as shown in the accompanying illustration.

It will be understood that the coffin-plate 30 and handle-plate are the same, except that the handle-plate will be provided with sockets, such sockets being indicated by broken lines in the illustration; but this construction is immaterial to the design, the outline of the 35 plate and its ornamentation being the same in either case.

I claim—

The herein-described design for coffin-trimmings, as shown in the accompanying illustration. 40

In testimony whereof I have signed this specification in the presence of two subscribing witnesses.

WILLIAM E. STEVENS.
